SPARK PLUG

Joseph A. Jeffery, Detroit, Mich., assignor to
 Champion Spark Plug Company, Toledo, Ohio,
 a corporation of Delaware

Application March 23, 1942, Serial No. 435,864

7 Claims. (Cl. 123—169)

This invention relates to spark plugs and particularly to gaskets therefor, and has for its primary object the provision of an efficient gas tight seal between the core and shell of a spark plug.

It has long been recognized that as spark plugs are subjected to elevated operating temperatures, the gasket seal between the insulator and shell is likely to be so modified, due to its expansion and contraction, as to be no longer effective. Obviously, in most spark plugs the coefficient of expansion of the core is materially less than that of the shell, so that if the parts were to fit tightly together when cold they would tend to move apart when heated. Such movement would create a space through which gas leakage could occur which would result in heat conditions in the core so severe as to upset the operation of the plug. To overcome this the practice has been to interpose a metal gasket which would expand as the shell expanded and thus fill the space created by the increased temperature. Copper has been most widely used for this purpose, and while its operation is satisfactory for most spark plugs, it is subject to distinct disadvantages. First, its coefficient of expansion is so great that it is likely to stress the core to the point of rupture if the temperature is carried too high. Second, its great expansion relative to the insulator may result in scoring the gasket and consequent disruption of the seal which it is intended to effect. Other expedients have been tried but to my knowledge all of them involve the application of a single metal of a coefficient of expansion considerably greater than the insulator and which, therefore, moves relative to the insulator when heated.

An important object of the present invention is to overcome the above and other disadvantages by providing a novel, simple and inexpensive gasket which functions in an efficient manner.

Other objects and advantages of the invention will become apparent as the description proceeds, reference being had to the accompanying drawings, in which—

Figure 1 is a central vertical section of a spark plug incorporating the present invention, the insulator being shown in full; Fig. 2 is an enlarged central vertical section of one form of gasket, and Figs. 3 and 4 are similar sections of modified forms of the gasket.

Referring to the drawing, the spark plug shown consists of a ceramic insulator 1 seated in a metal shell 3. The usual center electrode 5 is carried by the insulator and forms a spark gap

with a side electrode 7 extending from the shell.

As is customary, the shell is provided with a sloping internal shoulder 9 opposite which is a congruously sloping enlarged portion 11 of the insulator. These surfaces are separated by a gasket 13. As previously stated, the gasket 13 has usually been formed from a metal having a higher coefficient of expansion than the ceramic insulator and frequently having a higher coefficient of expansion than the metal shell.

According to the present invention, the gasket 13 is formed of a plurality of superposed layers of dissimilar metals, two being shown in the present instance, one layer being designated 13^a and the other 13^b. The upper layer 13^a is formed of a metal such that its coefficient of expansion is approximately that of the insulator. For example, if the insulator material has a coefficient of expansion of 7×10^{-6} per degree C., any malleable alloy in the range of 6×10^{-6} to about 10×10^{-6} may be used, since the relative motion between the parts during expansion will be so small that, in effect, the parts move together. Otherwise expressed, an alloy having a coefficient of expansion within the range of 10% less than and 20% greater than the coefficient of expansion of the insulator is preferred, although the upper limit may be increased in certain instances. If the coefficient of expansion is too low relative to the insulator, the gasket layer 13^a may take a permanent set when heated and thus distort. An alloy of the composition Ni 36.25%; Co 11.75%; FeSi .50% and Fe 51.50% is suitable, as its coefficient of expansion is 7.4×10^{-6} per degree C.

The lower layer 13^b adjacent the shell is formed of a malleable metal having a coefficient of expansion equal to or slightly less than that of the shell, preferably not more than 30% less than the shell. For example, the steel commonly used in the manufacture of spark plug shells has a coefficient of expansion of about 15×10^{-6} per degree C., so that any malleable metal having a coefficient of expansion in the range between 12×10^{-6} and 15×10^{-6} would be suitable. Preferably, the coefficient of expansion is very close to that of the shell, and towards the upper end of the range given.

By placing the insulator in contact with a gasket portion which expands at a substantially identical rate, movement at this interface is substantially eliminated. A similar condition will exist at the interface between portions 13^b and the shoulder of the shell. Consequently, the movement is concentrated at the interface be-

tween the two gasket portions which therefore slide over one another.

By selecting a metal for the gasket portion 13^b which expands somewhat less than the shell metal, the movement of the gasket may be divided into a sliding movement at the two faces of this portion of the gasket. Thus, the "joint" between the insulator on one hand and the shell on the other possesses an inherent flexibility, so that no appreciable movement takes place at any plane.

In the preferred form shown in Figs. 1 and 2, the portions 13^a and 13^b are joined together in a welded bend which permits the independence of movement of the superposed portions.

In the form shown in Fig. 3, the portions of the gasket are entirely separate, while in the form shown in Fig. 4 the two portions are joined together over their entire surfaces. In this latter form, stress of the molecules at the interface takes the place of actual movement at that point, so that this form may be advantageously employed where the difference in the coefficients of expansion of the two portions is relatively small.

The insulator 1 is held to its seat in the shell 3 in any suitable manner, as is well understood in the art. In the construction shown in Fig. 1 which represents a "one-piece" plug, the insulator is held in by a body of powdered material 6 which is tamped into place over an upper shoulder 8 formed on the insulator 1, a gasket 10 being interposed between the body of powder and the insulator. In order to protect the powdered material 6 against erosion and to assist in holding the assembly together the upper portion of the shell 3 is rolled in over the powder as at 12.

While the invention has been described in connection with a particular form and disposition of the spark plug parts, it will be appreciated that it is equally applicable to other forms and that such modified applications are included within the scope of the appended claims.

Having thus described by invention, what I claim as new, and desire to secure by United States Letters Patent, is:

1. In combination with the insulator and metal shell parts of a spark plug or the like, a gasket interposed between said parts comprising superposed layers of metal having different coefficients of expansion, the metal having the lowest coefficient of expansion being disposed adjacent the insulator part.

2. A combination in accordance with claim 1 in which the layers of metal of the gasket are joined together at one edge.

3. A combination in accordance with claim 1 in which the layers of metal of the gasket are joined together throughout their entire contacting areas.

4. In combination with the insulator and metal shell parts of a spark plug or the like, a gasket interposed between said parts comprising at least two superposed layers of metals having different coefficients of expansion, the coefficient of expansion of the metal adjacent the ceramic part being approximately the same as the coefficient of expansion of the ceramic part, and the metal adjacent the shell part having a coefficient of expansion approximately the same as the shell part.

5. In combination with the insulator and metal shell parts of a spark plug or the like, a gasket interposed between said parts comprising superposed layers of metals having different coefficients of expansion, the metal adjacent said insulator part having a coefficient of expansion of from 6×10^{-6} to 10×10^{-6} per degree centigrade and the metal adjacent the shell part having a coefficient of expansion equal to or less than the coefficient of expansion of the shell part.

6. In combination with the insulator and metal shell parts of a spark plug or the like, a gasket interposed between said parts comprising superposed layers of metals having different coefficients of expansion, the metal adjacent the insulator part having a coefficient of expansion within the range of 20% greater or 10% less than the coefficient of expansion of the insulator part and the metal adjacent the shell part having a coefficient of expansion less than that of the shell part.

7. In combination with the insulator and metal shell parts of a spark plug or the like, a gasket interposed between said parts comprising superposed layers of metals having different coefficients of expansion, the metal adjacent the insulator part having a coefficient of expansion not more than 20% greater nor lower than 10% less than the coefficient of expansion of the insulator part, and the metal adjacent the shell part having a coefficient of expansion equal to or not more than 30% less than the coefficient of expansion of the shell part.

JOSEPH A. JEFFERY.
